RACING GAME APPARATUS

Charles L. Deihle, Irondequoit, N. Y.; Catherine J. Deihle executrix of said Charles L. Deihle, deceased

Application June 18, 1948, Serial No. 33,911

7 Claims. (Cl. 273—86)

1

This invention relates to amusement devices and, more particularly, to devices of this character in which a plurality of objects are individually movable in a manner affording a contest of speed, thus simulating a competitive race between the objects which may be made to represent animals or the like, on purpose of the invention being to provide a simple and convenient device of this character which is pleasing to operate and effective and reliable in its construction and functions.

Another object is the provision of a simple, manually operable device of this type, obviating the use of power motors with their attendant cost, weight and encumbrance, thus reducing the stresses on the parts and their liability to breakage and so affording a light, portable mechanism which is readily transported from place to place and installed in use.

Still a further object is the provision of a device having the above advantages with means affording certain automatic controls of the racing objects adding to the pleasure and convenience of operation of the parts.

To these and other ends the invention resides in certain improvements and combinations of parts, all as will be hereinafter more fully described, the novel features being pointed out in the claims at the end of the specification.

In the drawings:

Fig. 1 is an end elevation, partly in section, of an amusement device embodying the present invention;

Fig. 2 is an enlarged sectional plan view on the line 2—2 in Fig. 1;

Fig. 3 is a diagrammatic illustration of an automatic trip device and its electrical circuit forming part of the invention;

Fig. 4 is a diagrammatic view of an automatic indicating means and its electrical circuit;

Fig. 5 is an enlarged end elevation of the operating board and its parts as shown in Fig. 1;

Fig. 6 is an enlarged sectional elevation on the line 6—6 in Fig. 7;

Fig. 7 is an enlarged front elevation, partly in section, of the display board shown in Fig. 1;

Fig. 8 is a sectional elevation on the line 8—8 in Fig. 7;

Fig. 9 is an enlarged elevation of driving means shown in Fig. 1 with the parts in driving position;

Fig. 10 is a sectional view on the line 10—10 in Fig. 9;

Fig. 11 is a view similar to Fig. 9, but showing some of the parts in released or idle position;

2

Fig. 12 is an enlarged sectional elevation on the line 12—12 in Fig. 11;

Fig. 13 is a view of some of the parts shown in Fig. 12, but arranged in separated relation for better illustration;

Fig. 14 is a view similar to Fig. 13 but with the parts in the relative positions which they occupy when in driving arrangement;

Fig. 15 is a sectional plan view on the line 15—15 in Fig. 12;

Fig. 16 is an enlarged sectional elevation on the line 16—16 in Fig. 7, showing a belt tensioning means;

Fig. 17 is a front elevation of parts shown in Fig. 16 with the belts omitted;

Fig. 18 is a rear view of the parts shown in Fig. 17;

Fig. 19 is an enlarged sectional view on the line 19—19 in Fig. 17;

Fig. 20 is a front elevation of one of the animated racing objects with adjacent portions of the display board;

Fig. 21 is a sectional elevation on the line 21—21 in Fig. 20;

Fig. 22 is a sectional plan view on the line 22—22 in Fig. 20, and

Fig. 23 is a diagrammatic view showing the arrangement of the driving belt on its supporting pulleys.

The preferred embodiment of the invention herein disclosed by way of illustration, comprises a base indicated generally at 30 (Fig. 1), in the form of a substantially rectangular frame composed of a front beam 31 and a rear beam 32 connected by side rails 33. At the forward side of the base is an upstanding frame portion indicated generally at 34, composed of corner posts, as 35, having their lower ends fixed to the base and connected by rails, as 36 and 37. This frame supports at its top a horizontal operating board 38, above which are a plurality of two or more operating handles, preferably in the form of rotatable wheels 39 having knobs 40 by which they may be rotated to operate the machine as hereafter described.

Fixed to the rear side of the base is an upright frame, indicated generally at 41, composed of vertical end posts 42 having their lower ends fixed to the base and connected by upper and lower rails, 43 and 44. The posts are braced by inclined struts, as 45, which preferably support a plurality of steps 46 for use by the operator in reaching the display board and its racing objects, or for supporting and displaying prizes for the players, or the like.

Rails 43 and 44 of the upright rear frame preferably carry a number of forwardly projecting upper and lower brackets, 47 and 48, to the forward ends of which is fixed the display board 49 (Figs. 7 and 8) formed with a plurality of horizontally spaced, vertical slots, as 50, through which the racing objects on the front of the board are supported by means located in its rear, as hereinafter described. Located rearwardly of and on opposite sides of each slot 50 are guide means supplied by vertical guide rods 51 having their upper and lower ends supported in the brackets 47 and 48, respectively. Coiled about the lower end of each rod is a compression spring 52 for cushioning the descent of the racing objects 53 (Fig. 20) each in the form of a metal plate having an outline representative, in the present instance, of a climbing monkey with articulate limbs supported and actuated as hereinafter described, there being one of these racing objects 53 to correspond with each of the operating handles 40 on the operating board. The players stand in front of the operating board 38 and each, by means of his handle 40, through mechanism presently to be described, moves the corresponding object 53 upwardly on the display board, the objects moving in parallelism with each other in a contest of speed to reach the top of the board. While but two such operating handles and objects are shown in the present instance, any convenient number of them may be provided and the objects themselves, of course, may take various forms other than that of climbing monkeys as herein disclosed.

The operating mechanism for each of the racing objects preferably comprises upper and lower brackets, 54 and 55 (Fig. 5), fixed on and projecting rearwardly from the operating board, as shown. These brackets are formed with bearings rotatably supporting a vertical shaft 56, the upper end of which projects upwardly through the operating board 38 and has fixed thereon the wheel 39 and handle 40 described above. The hub of the wheel, bearing against the upper face of bracket 54, supports the shaft against vertical movement. Rotating freely on each shaft 56 adjacent its lower end are a pair of grooved pulleys 57 and 58, the upper pulley 57 being supported in place by a collar 59 fixed to the shaft and the lower pulley 58 being supported by clutch means hereinafter described. The upper pulley 57 is somewhat larger in diameter than the lower pulley so that as both are rotated by the same shaft 56, the upper pulley has a greater peripheral speed.

Upper pulley 57 is releasably clutched to shaft 56 by means of a speed governor comprising a head 60 (Fig. 5), fixed to the shaft 56. Pivoted oppositely on the head are depending arms 61 which are pivotally connected by links 62 with a lower head 63 sliding on shaft 56, as shown. Coiled tension springs 64, fixed to arms 61 and to pins in the shaft 56, tend to swing the arms 61 downwardly and so lower the sliding head 63, but the lower ends of arms 61 carry weights 65 which tend, at high speeds, to swing the arms 61 upwardly and outwardly by centrifugal force so as to raise the lower sliding head 63, this device being in the nature of the known centrifugal governor mechanism, so that a more detailed description thereof is unnecessary.

Depending from the governor head 63 are pins 66 arranged, in the lower positions of the head 63, to engage pins 67 projecting upwardly from a plate 68 fixed on the upper side of the upper

pulley 57 (Figs. 9 and 10). Plate 68 has a depending sleeve which forms the bearing hub of the pulley, as shown. It is apparent from this construction that while the operating handle 40 is rotated at moderate speeds, the governor head 63 remains sufficiently lowered so that its pins 66 engage pins 67 and rotate the pulley 57. At higher speeds, however, the governor head is pulled upwardly, thereby disengaging the pins and unclutching and releasing the pulley 57 for rotation relative to the shaft 56.

The lower pulley 58 has a plate 69 fixed to its upper side and formed with a hub or sleeve 70 depending through and below the pulley and serving as a bearing hub for rotatably supporting the pulley on the drive shaft. The lower end 71 of sleeve 70 is formed with a plurality of notches 72 and provides the upper face of a clutch for releasably clutching the pulley to the drive shaft. The lower and cooperating clutch face is provided on the upper end 73 of a sleeve 74 which is formed with a plurality of upwardly projecting clutch teeth 75 for engagement in the notches 72 of the upper face. Sleeve 74 has a keyway 76 cut inwardly from its lower end and slidably embracing a key 77 fixed to shaft 56, so that the sleeve is keyed to rotate with but slide longitudinally on the shaft. The sleeve is preferably mounted to slide on one or more telescoping inner sleeves 78 and 79, with similar keyway slots for engagement with the key 77. These inner sleeves are for the purpose of conveniently increasing the diameter of the shaft and reducing the thickness and weight of the clutch sleeve 74.

For clutching and unclutching the lower pulley 58, the lower end 80 of clutch sleeve 74 projects into proximity with the upper surface of a lever 81 having its inner end pivoted at 82 on bracket 55 of the operating board. Pivotedly connected with opposite sides of the lever are a pair of links 83 having their upper ends pivotally connected with a collar 84 slidably engaging the outside of the clutch sleeve 74. Sleeve 74 has screw heads 85 projecting outwardly from opposite sides of the lower end thereof in position to be engaged by the lower end of collar 84 for positively moving the sleeve 74 downwardly by downward movement of the collar for releasing the clutch parts. These parts are so arranged that in the lowered position of lever 81 (Figs. 5, 11 and 12), clutch sleeve 74 is in its lowered disengaged position. When lever 81 is raised, however, it engages the lower end of sleeve 74, sliding it upwardly until the clutch teeth 75 on its upper end are engaged in the notches 72 of the clutch face of the pulley 58, to clutch it onto the drive shaft 56, the parts being then in the position shown in Figs. 1, 9 and 10. As the lever is lowered, collar 84 strikes screws 85 to lower sleeve 74 and positively disengage the clutch parts to release pulley 58 for free rotation on the drive shaft, while supported on the upper end of one of the inner sleeves 78 or 79.

Lever 81 for thus actuating each lower drive pulley clutch is operated automatically by a device which is tripped by the object winning the race as it reaches its uppermost position. For this purpose, each lever 81 has pivoted at 86 on its outer end a link 87 (Figs. 1 and 5), the other end of which is pivoted at 88 to an arm 89 fixed on a shaft 90 extending from end to end of the base and mounted to rock in bearings 91 on its end rails 33. Fixed to shaft 90, adjacent to one end of the operating board, is an arm

92 having fixed on its other end a lug 93, for engagement with the forward end of a latch or dog 94 pivoted at 95 on a bracket 96 on the adjacent post of the operating board. The rear end of the dog is pulled downwardly by a tension spring 97 against a stop pin 98, and this rear end of the dog is also pivoted to the plunger 99 of a solenoid 100 connected in circuit with a switch of the trip device operated by the winning object, as hereafter described.

It is evident that arm 92 may be latched in upright position by engagement with dog 94, as shown in Fig. 1, so as to rock the shaft 90 and raise each of the levers 81 to clutch the lower pulley 58 to the drive shaft. As any one of the racing objects first reaches the upper limit of movement, it closes its switch in the circuit of the trip device to energize the solenoid 100, swinging dog 94 to release arm 92 which is thrown forwardly by the weight of the parts until its bevelled free end 101 strikes a stop bracket 102 on the frame of the operating board. This releasing movement is assisted by the weight also of an arm 103 fixed on shaft 90 and serving also as means for manually rocking shaft 90 to latch arm 92 in its upright position with the lower pulleys clutched to the drive shaft. For this purpose, arm 103 has fixed to its free lower end a cord 104 passing around pulleys on the operating board and provided at the rear side thereof with a knob 105 by means of a pull on which the operator may reset the apparatus for a contest.

The releasing solenoid 100 is connected in circuit (Figs. 3, 7 and 8) with any suitable source of power 106 and with a switch for each object having a lever 107 pivoted at 108 on a bracket 109 on the upper rail 43 of the display board, these switches being connected in parallel with the source of power, and the solenoid. Each switch is normally held open by a tension spring 110 and the switch arm 107 lies in the path of a lug 111 of insulating material fixed on an upper cross arm of the corresponding object, as more fully hereafter described. As any racing object approaches the upper limit of its movement, its lug 111 strikes and moves the corresponding switch arm 107 to close the switch, the winning object being the first to close the circuit through the solenoid to release the lower drive pulley and allow all of the objects to fall back to starting position for another race, as hereafter described. The winning object similarly engages and operates a second switch arm 112 (Figs. 4 and 7), on the opposite side of its raceway, for closing the circuit of a lamp to indicate the particular object winning the race. Arm 112 is pivoted at 113 on a bracket 114 on the display board and is moved by the object to close switch contacts in a circuit including a suitable source of power 115 and a lamp 116. A cord 117 is provided in convenient position to be pulled by the operator, for reopening the switch for a subsequent contest.

Each racing object 53 is preferably mounted on a frame, indicated generally at 118 (Figs. 20-22), having an upper cross arm 119 elongated to engage and operate the above described switches and a lower cross arm 120, both slidably engaging the guide rods 51 on opposite sides of each raceway slot 50. Projecting forwardly from the top and bottom of the body portion of each frame 118, through the corresponding slot 50, are upper and lower posts 121 and 122, to the forward ends of which the body portion 53

of the racing object is secured in front of the display board. This object body, in the present instance, is outlined to represent the figure of a monkey having an arm 123 pivoted on a post 124 projecting forwardly from the object body on which also a leg 125 is similarly pivoted. Each of these arm and leg parts is actuated by similar means so that a description of such means for the leg will suffice for both. A pin 126 (Fig. 22) is fixed in the leg part and engaged in a slot 127 in an arm 128 pivoted at 129 on a rear plate 130 attached to the object body. Arm 128 has a slot 131 in which is engaged a pin 132 fixed eccentrically in the forward end of a sleeve 133 fixed on a shaft 134 journalled in the body of the frame 118 and extending through the rear side thereof where the shaft has fixed thereon a grooved pulley 135. The similar actuating means for the arm part of the object comprises a shaft 136, journalled in the object frame and having fixed thereon a grooved pulley 137, located above the pulley 135. It is evident from this construction that rotation of the pulleys 135 and 137 serves to swing the arm and leg parts 25 of the object so as to simulate a climbing action as the pulleys are rotated and the object is raised and lowered by belt means which will now be described.

The means for raising and lowering each racing object comprises an endless flexible belt member, indicated generally at 138, preferably made of a flexible cotton cord, which has been found most efficient for frictionally gripping the grooved pulleys with a minimum of tension, pulley friction and driving force. This cord is arranged in loops passing around each of the pair of the driving pulleys and each of the pair of pulleys on each object, as shown diagrammatically in Fig. 23. That is, this cord has one loop 139 passing around the upper driving pulley 57. One side 140 of this loop passes around an idler pulley 141 on a tensioning device, hereafter described, at the bottom of the display board, and thence upwardly and around the lower pulley 135 of the object from which it passes around an idler pulley 142 and thence, as at 143, to the lower driving pulley 58. From the opposite side of this pulley, the cord passes, as at 144, around an idler pulley 145 and thence upwardly and around an idler pulley 146 on a fixed trunnion at the top of the display board. From this idler pulley, the cord passes, as at 147, around the upper pulley 137 of the object and thence, as at 148, around a second idler pulley 149 on a trunnion fixed at the top of the display board. From this idler pulley, it passes downwardly, as at 150, around an idler pulley 151 and back to the loop 139 engaged with the upper drive pulley 57.

The object pulleys are preferably of the same diameter, but the upper driving pulley 57 is larger in diameter than the lower driving pulley, so that in the rotation of these pulleys by the same driving shaft, the upper pulley has a greater peripheral speed. As a result, the reach 143 of the belt leading from the upper pulley 137 of the object is pulled upwardly at a higher rate of speed than the reach 147 of the belt leading to the same pulley, since the reach 147 is supplied by the lower driving pulley rotating at a lower peripheral speed. This tends to pull the object upwardly, since the loop of the belt around the lower object pulley 135 is correspondingly payed out by a reach of the belt supplied by the faster upper pulley 57. Rotation of the operating wheel 39 or its handle 40 thus acts to raise the cor-

responding object up its runway, accompanied by animated motion of its articulate arm and leg parts, so long as both of the driving pulleys 57 and 58 are clutched to the rotated driving shaft. On the unclutching or release of either driving pulley, however, the cord is freed so that the weight of the object causes it to drop back along its raceway, as hereafter more fully described.

It has been found advantageous, as stated, to make the belt member of flexible cotton cord material, but such material is subject to stretching and shrinking under atmospheric changes, tending to either cause the cord to slip on the pulleys or to become so taut as to frictionally bind the pulleys and particularly the driving pulleys even after release of the clutches. It has been found that this difficulty can be overcome, however, by the provision of automatic tensioning devices in conjunction with the mounting of the idler pulleys 141, 142, 145 and 151 at the bottom of the display board. To this end, these pulleys are all rotatably mounted on a shaft 152 (Figs. 16-19), fixed in a bracket 153 projecting forwardly from a slide 154 having laterally extending rollers 155 engaged in vertical slots 156 in the side bars 157 of a frame fixed to the rear rail 32 of the base. The side bars 157 are additionally connected by upper and lower cross bars 158 and 159 at the forward side of the frame so as to leave its rear side unobstructed. Slide 154 is provided on its rear side with a chute 159^a having an open top and adapted to slidably receive a suitable number of weights 160 for pressing the idler pulleys downwardly to tension the several loops of the belt which also tend to distribute and equalize the tension as between the different loops in view of the endless nature of the belt. By this means the belt is automatically maintained with a uniform suitable tension for gripping the several pulleys, but without an excessive degree of belt pull.

In operation, with the lever 92 latched in position to raise all of the levers 81 and clutch the lower pulleys 58 to their respective drive shafts, and with the objects in their lower or starting position, the players begin at a given signal to rotate their respective handles 42, each endeavoring to be the first to raise his object to the top of its raceway. When any of the objects, however, is raised at more than a predetermined rate of speed, the centrifugal governor operates to unclutch the upper driving pulley from the drive shaft, with the result that the weight of the object tends to impart to the belt a movement in addition to that still imparted by the lower driving pulley, so that the free upper driving pulley 57 is turned at a less peripheral speed than the lower driving pulley 58, or is held stationary, or even reversed, depending upon various conditions, such as weight and friction of the parts, which may be designed, however, to control within limits the speed of descent of the object. When the speed of the operating handle is sufficiently decreased to correct this difficulty, the centrifugal governor again clutches the upper driving pulley 57 to the drive shaft and the rise of the object is resumed. This unexpected and adverse result of excessive speed of rotation of the operating handle injects an element of surprise which adds to the zest of the competition and the amusement afforded by the device.

As the leading object approaches the uppermost or winning position, it closes the switch

lever 107, thereby unlatching lever 92, which, by its descent, releases all of the lower driving pulleys so that all of the objects automatically descend. At the same time, however, the winning object also closes switch lever 112 to light the signal lamp and indicate the winner until the switch is opened by pulling cord 117 to ready the apparatus for another contest.

The display board is preferably painted with attractive jungle or other appropriate scenery and the apparatus affords a highly pleasing game of skill embodied in a construction which is relatively light and portable, as well as easy and convenient to install and operate.

It will thus be seen that the invention accomplishes its objects and while it has been herein disclosed by reference to the details of a preferred embodiment, it is to be understood that such disclosure is intended in an illustrative, rather than a limiting sense, as it is contemplated that various modifications in the construction and arrangement of the parts will readily occur to those skilled in the art, within the spirit of the invention and the scope of the appended claims.

I claim:

1. An amusement device comprising upright guide means, an object movable on said guide means in one direction by gravity and provided with driven pulleys, driving pulleys, supporting means on which said driving pulleys are freely rotatable, continuous belt means having loop portions engaging said driving and driven pulleys, respectively, manually operable means for rotating said driving pulleys at different peripheral speeds, respectively, and varying the length of said loop portions to move said object in the other direction, said manually operable means having a releasable connection with one of said driving pulleys, speed governor means controlling said releasable connection, said driving means having a releasable clutch connection with the other of said driving pulleys, and a trip device actuated automatically by said object in the raised position thereof for positively releasing said clutch connection from the other of said driving pulleys for gravity descent of said object.

2. An amusement device comprising upwardly extending guide means, an object movable on said guide means in one direction by gravity and provided with driven pulleys, driving pulleys, supporting means on which said driving pulleys are freely rotatable, an endless flexible cotton cord member arranged in a series of loops each engaging one of said pulleys, driving means having releasable clutch connections with said driving pulleys for rotating the same at different peripheral speeds to vary the lengths of said loops and raise said object, said object being adapted for movement by gravity to rotate said driving pulleys when said driving pulleys are released by said clutch connections, and gravity actuated tensioning devices engaging loops of said cord member for automatically maintaining a constant pull on and frictional resistance in said pulleys under variations in the length of said cord member during variations in atmospheric conditions.

3. A portable amusement device comprising a base, an operating board at the front of said base, a vertical display board at the rear of said base formed with a plurality of horizontally spaced, vertically extending slots, vertical guide means rearwardly of each slot, a frame slidable on each guide means and having supporting means extending forwardly through said slot and provided

with pulleys rearwardly thereof, an object on said frame supporting means having articulate parts, actuating means connecting said pulleys through said slots with said articulate parts to effect articulate movement thereof, a pair of driving pulleys for each of said objects, a flexible belt member connecting said first mentioned pulleys and driving pulleys, driving means for each of said pairs of driving pulleys having a manually operable member located on said operating board, said pulleys being freely rotatable on said driving means, releasable clutch means connecting said driving means with each of said pulleys thereof, and means for automatically releasing said clutch means and said driving pulleys for rotation by said belt member to permit said object to descend by gravity.

4. An amusement device as specified in claim 3 comprising speed responsive means for releasing one of said clutch means, and means for releasing the other of said clutch means comprising a trip device actuated by the corresponding object in its uppermost position.

5. An amusement device comprising upright guide means, an object movably mounted on said guide means for descent by gravity and provided with pulleys, said object having articulate parts having actuating connections with said pulleys, driving pulleys, supporting means on which said driving pulleys are freely rotatable, an endless cord member looped about said first mentioned pulleys and said driving pulleys, manually operable means for rotating said driving pulleys at different peripheral speeds to vary the lengths of the looped portions of said cord member to raise said object, said manually operable means having a releasable connection with one of said driving pulleys, a speed governor controlling said releasable connection, releasable clutch means connecting said manual means with the other of said driving pulleys, and means actuated automatically by said object in the raised position thereof for releasing said clutch means and said other pulley for rotation by said cord member to permit gravity descent of said object.

6. An amusement device comprising upright guide means, an object movably mounted on said guide means for descent by gravity and provided

with articulate parts, driven pulleys on said object provided with eccentric actuating means, connections between said actuating means and said articulate parts for producing animated movements thereof, driving pulleys, a flexible belt member arranged in loops engaging said driven pulleys and driving pulleys, respectively, manually operable means for rotating said driving pulleys at different peripheral speeds, respectively, to vary the lengths of said loops and raise said object, and a releasable clutch connection between said manual means and one of said driving pulleys for releasing said driving pulley for reverse rotation by said belt member to permit gravity descent of said object.

7. An amusement device comprising upwardly extending guide means, an object movable on said guide means in one direction by gravity and provided with driven pulleys, driving pulleys, supporting means on which said driving pulleys are freely rotatable, flexible belt means having loops engaging said driving and driven pulleys, respectively, driving means having releasable clutch connections with said driving pulleys for rotating the same at different peripheral speeds to vary the lengths of said loops and raise said object, said driving pulleys being rotatable by said belt means when said driving pulleys are released by said clutch connections to permit said object to fall by gravity, and adjustable tensioning means for said belt member for maintaining a uniform belt pull on and frictional resistance in said pulleys.

CHARLES L. DEIHLE.
